BURT L. FLAHERTY, OF DAYTON, OHIO, ASSIGNOR, BY DIRECT AND MESNE ASSIGNMENTS, TO CENTRAL HEATING EQUIPMENT CORPORATION, OF DAYTON, OHIO, A CORPORATION OF OHIO

CHIMNEY

Application filed March 22, 1930. Serial No. 438,087.

This invention relates to chimneys and has special reference to the construction of the lower parts of such chimneys.

One important object of the invention is to provide an improved chimney construction so arranged that gases of combustion and the like entering the chimney from the breeching or other conduit will be changed from flow in a horizontal direction to flow vertically up the chimney in such manner as to neither produce back pressure in the breeching nor retardation in the chimney by eddies and counter-currents.

A second important object of the invention is to provide an improved chimney construction wherein a curved bottom is provided at the breeching opening which curves upwardly and rearwardly from the bottom of said opening into the back wall of the chimney.

20 A third important object of the invention is to provide an improved chimney construction wherein the chimney, at the junction of the breeching opening and vertical parts is interiorly enlarged and shaped at the front and back to provide a curved path for the gases of combustion.

A fourth important object of the invention is to provide an improved chimney construction having a curved flue portion of the kind above noted and provided with a soot and cinder chamber below said curved flue portion.

With the above and other objects in view, the invention consists in general of certain novel details of construction and combinations of parts hereinafter fully described, illustrated in the accompanying drawings and specifically claimed.

40 In the accompanying drawings like characters of reference indicate like parts in the several views, and:

Figure 1 is a side elevation partly showing a vertical section taken centrally through the front and back walls of the chimney;

Figure 2 is a section of the completed chimney on the line 2—2 of Figure 1;

Figure 3 is an enlarged section similar to Figure 1 but showing the chimney partly completed;

Figure 4 is a section on the line 4—4 of Figure 3;

In the construction of a chimney as here shown there is provided the usual base or foundation 10 principally below the ground. 55 On this is erected a chimney having a front wall 11, rear wall 12 and side walls 13. In one of these walls is formed the usual clean-out door 14 and the front wall 11 is provided, at some distance above the base with the 60 breeching opening 15 wherein is received the terminal end of a breeching 16.

Extending from one side wall to the other and slightly below the level of the interior bottom face of the breeching are spaced 65 T's 17 and at the rear wall there is similarly positioned an angle bar 18. At the front of the grid thus formed is a horizontal door frame 19 normally supporting a trap door 20 forming part of the bottom of the chimney 70 flue. Bridging the angle bar and T's are bricks 21 which form, with the metal parts, the roof or a soot or cinder pit 22. Successive courses of bricks 23 are supported on the rear of this floor and the forward faces 75 of these bricks are so formed as to present a smooth cylindrical surface 24 merging into the floor at its forward end and into the inner face of the rear wall 12 at its rear and upper end. This surface is preferably grouted 80 with fire clay so as to eliminate the results of any irregularities in the brick work.

The inner angle of the front wall 11 just above the opening 15 is chamfered as at 25, and the upper part of the breeching is cut back at this chamfered portion as at 26. For some distance above the parts just described the internal angles at the junction of the chimney walls are filleted as at 27 to eliminate any eddies or dead air spaces 85 which could tend to retard flow through the chimney. It will be noted that the distance between the surfaces 24 and 25 is considerably greater than the height of the breeching or the distance between the front and rear chimney walls. Also, the distance between the side walls is greater than the width of the breeching.

By this means gases from the breeching pass first into an enlarged chamber having 100

front and rear walls shaped to change the direction of flow of such gases from horizontal to vertical in a smooth and easy manner without setting up eddies or producing 5 back pressure in the breeching. This chamber may be termed an expansion chamber and from the expansion chamber the gases pass easily into the vertical or uptake portion of the chimney also without producing 10 eddies.

There has thus been provided a simple and efficient device of the kind described and for the purpose specified.

It is obvious that changes may be made in 15 the form and construction of the invention without departing from the principles thereof. It is not, therefore, desired to confine the invention to the exact form herein shown and described but it is desired to include all 20 such as come within the scope claimed.

Having thus described the invention, what is claimed is:—

1. The combination with a chimney having front, rear and side walls, said front wall 25 having an inlet opening; of a floor substantially level with the bottom of said opening at its front edge and curving from a line spaced from the front edge upwardly to the inner surface of the rear wall, the inner 30 top edge of the opening being chamfered sufficiently to permit free flow of gases there past, the curved flue thus formed being of greater cross-sectional area than the opening to form an expansion chamber.
- 35 2. The combination with a chimney having front, rear and side walls, said front wall having an inlet opening; of a floor substantially level with the bottom of said opening at its front edge and curving from 40 a line spaced from the front edge upwardly to the inner surface of the rear wall, the inner top edge of the opening being chamfered sufficiently to permit free flow of gases there past, the curved flue thus formed being 45 of greater cross-sectional area than the opening to form an expansion chamber, said floor being spaced above the bottom of the chimney to form a soot chamber, said chimney having a door affording access to the soot 50 chamber from outside the chimney, and a clean-out door in the floor at the forward part thereof.

In testimony whereof I affix my signature.
BURT L. FLAHERTY.
